UNITED STATES PATENT OFFICE

CHAUNCEY ARNOLD DUTTON, OF SHAKER HEIGHTS VILLAGE, OHIO, ASSIGNOR, BY
MESNE ASSIGNMENTS, TO FERRO ENAMEL CORPORATION, OF CLEVELAND, OHIO, A
CORPORATION OF OHIO

FURNACE

Application filed February 19, 1930. Serial No. 429,482.

This invention relates to furnaces, particularly to those of the type used in the art of burning enamel ware, wherein the furnace is constructed in the form of a long corridor, closed at one end, through which the work is carried by a conveyor arranged in the form of a U. The entrance and exit mouth are side by side at one end of the corridor, the heating chamber being at the closed end which is remote from the mouth, and the section between the heating chamber and the mouths constituting a heat interchange wherein the outgoing work gives off heat to the incoming work while both are moving slowly along the substantially parallel legs of the U-shaped track. For convenience such a furnace is hereinafter referred to as U-shaped.

A problem of great importance to be solved in the economical operation of such furnaces is the retention of heat. A further problem is to accomplish effective interchange of heat between the hot outgoing and cold incoming ware, whereby the former is gradually cooled down before passing into the outside air, and the heat instead of being wasted is employed to bring the latter by gradual increase as near as may be to the temperature of the heating chamber, thereby reducing the heat consumption as well as producing a more perfect finish of the enamel by the avoidance of sudden changes in temperature.

Among the objects of this invention is the provision of relatively simple and effective means for solving the problems outlined above, and particularly the provision of air screens for preventing the escape of heat from the furnace doorways which will not interfere with the conveyor operation and which will materially aid the heat interchange process.

Another object is to promote the heat interchange by inducing a transverse circulation of air in the heat interchange chambers so that the air which passes over the outgoing hot ware will contact with the incoming cooler ware substantially opposite, and with the result that extreme difference in temperature between the opposite pieces of burned and unburned work at any point along the conveyor will be materially reduced.

Other objects of the invention and the method of securing the same will appear from the following specification, which, taken in conjunction with the accompanying drawings, sets forth a preferred form of practical application of the principles of my invention. It is to be understood, however, that the specifications and drawings are by way of example and not limitation, and that other embodiments are within the purview of the invention.

Fig. 1 is a diagrammatic plan view of a furnace showing the application of various features of my invention thereto; Figs. 2, 3 and 4 are, respectively, the front and side views and top plan view of a heat interchange air screen apparatus, the front and side views being partly sectional and partly elevational; Fig. 5 is a partial detail of the conveyor and hood, approximately on the line 5-5 of Fig. 3; Figs. 6, 7 and 8 are respectively front, side and top views of a modified form of apparatus for producing an air screen, corresponding to Figs. 2, 3 and 4, respectively, and Fig. 9 is a view on the line 9-9, Fig. 1, showing the circulation of air within the heat interchange chamber.

Referring to Fig. 1, the furnace will ordinarily be built in the form of a long chamber surrounded by suitable refractory walls 1, and having a heating chamber 2, closed by the end wall 3, and the heat interchanger chamber 4, usually much longer than the heating chamber; the relative proportions being in accordance with the nature of the treatment for which the furnace is designed. A pillar 5 divides the furnace mouth into two doorways 6 and 7. The work, generally indicated by the reference character 8, illustrated as being carried through the furnace by a continuous conveyor system 9 of the trolley type, and conveniently comprising a chain 10, (Fig. 3), driven in the direction of the arrows in Fig. 1 by suitable means not shown and not constituting a part of my invention. The work is suspended from the conveyor through rods 11 which depend through a U-shaped slot in the top of the furnace. Shoe plates 13 slide along suitable tracks and cover the top of the slot and prevent the escape of

heat therethrough. The shoe plates overlap longitudinally and are moved by the rods in their travel around the furnace. The shoe plates are free to move up and down on the upper part of the rods 11, being supported by collars 11' on the rods when off the tracks. The shoe plates are raised from and lowered to the collars 11' near the open end of the furnace by shoe plate guides 12 which have downwardly inclined ends extending beyond the front wall of the furnace. The furnace and conveyor are of a type more fully described in the copending application of Leo W. Manion, Serial No. 364,477, filed May 20th, 1929, and will not be further described herein.

Referring now to Figs. 2, 3, 6 and 7, the doorways 6 and 7 are open. The prevention of drafts of air through these doorways, which would cause loss of heat, is accomplished by air screens, each consisting preferably of an upward blast of air across the entire width of each opening, as indicated by the arrows with solid shafts. In the form shown by Figs. 2 and 3 the air discharged from a blower 15, suitably located outside the furnace, is directed into a discharge duct 17 placed against the front wall of the furnace below the doorway 7 and having a suitable blast nozzle or slot 18 to direct the air upward in a thin stream the full width of the doorway. A hood 19 is secured across the top of the doorway, and is of sufficient width and thickness to collect the air stream. This hood, to be described in greater detail below, connects at one end with a conduit 20 which leads to the suction side of a second blower 21, the blast from which discharges through a discharge duct 22 and nozzle or slot 23 bearing the same relation to the doorway 6 that the duct 17 and nozzle 18 do to the doorway 7. Thus a similar upward air screen is created at the doorway 6, this screen being collected by a hood 24 and returned by a conduit 25 to the first blower 15.

Heretofore work coming out of the doorway 7 was at about 400° to 700° F. The air screen, moving upward in conjunction with the natural rising of the air from the hot ware, carries away a considerable quantity of this heat, which is in turn imparted to the work entering the furnace through the air screen in front of the doorway 6.

Figs. 6, 7, and 8 represent a modified form of air screen wherein a somewhat simpler arrangement is used. In this form air from the blower 30 divides in the discharge conduit 31 and is driven up through two nozzles 32 corresponding to the nozzles 18 and 23, across the doorways 6 and 7 and collected in the respective hoods 33, from each of which it is returned by a common conduit 34 to the suction side of the blower 30. It is apparent that by this course of circulation the air which is driven past the hot work in the doorway 7

becomes mixed in the conduit 34 with the cooler air from the doorway 6, but that as soon as circulation has kept up for a few minutes the average will become greater than the temperature of the ingoing work, although it will always be less than that of the outgoing, so that a very material heat interchange will be produced by this form of air screen also.

I regard the construction of the intake hood as shown at 19, 24 and 36 as one of the outstanding features of my invention. Heretofore screens have been constructed with separate intake or discharge pipes and positioned near the top of the doorway on opposite sides of the path of the conveyor rods and on opposite sides of the slot in the roof of the furnace whereby the screen has been in effect divided in two parts at the top with a consequent loss in efficiency. My hood construction is based on the theory that the air of the screen having passed upwardly across the doorway of the furnace, can best be directed laterally across the path of the conveyor rods instead of being carried upwardly in divided paths on opposite sides thereof.

To this end the top wall 51 of the hood (see Fig. 5) lies substantially horizontal, although preferably inclined upwardly in the direction of the flow of air and underlies and closely contacts with the shoe plate guides 12. It will be seen particularly from Fig. 5 that the shoe plates 13 overlying the guides 12 form with the top wall 51 a continuous closed top wall for the hood, whereby all of the upwardly flowing air in the screen is diverted and carried laterally under the top wall into the intake conduits and thence to the blower. The inner or back side walls of the hood may comprise or lie adjacent to the front walls of the furnace so that the inner wall of the hood is continuous except for the slot in the roof of the furnace, which however, is wholly covered by the shoe plates, as shown in Fig. 4. The front wall of the hood extending as it does about a foot from the front wall of the furnace and parallel thereto is divided by a slot 53 longitudinally aligned with the major slot in the roof of the furnace to permit the passage of the work carrying rods 11. The shoe plate guides 12 (see Figs. 3 and 4) extend beyond the front wall of the hood and are thence inclined downwardly as at 12', whereby they raise and lower the shoe plates as they move toward or away from the furnace.

Those skilled in the art will appreciate that this hood construction will gather and receive all of the upwardly flowing air of the screen and conduct it without loss to the blower whence it is re-directed across the opening. Such means as baffle plates 52 (see Figs. 2 and 6) may be built into the hoods adjacent the intake conduits for the purpose of balancing and proportioning the flow throughout the body of the hood. The essential character-

istic of the hood construction is that the flow is directed laterally across the path of the conveyor rods under a completely closed top wall, whereby the screen is not divided or 5 split because of its relation to the conveyor and the work suspending rods.

Hitherto radiation alone has been depended upon to heat the cold work and cool the hot work in the chamber 4 of the furnace. However, a more effective interchange may be 10 brought about within this chamber 4 by giving the air therein a rolling motion or continual eddy, as represented diagrammatically by the circle of arrows 39 in Fig. 9.

A suitable apparatus to accomplish this is 15 illustrated in Figs. 1 and 9, the arrangement there shown comprising a series of openings 40, 41 arranged in pairs near opposite sides of the furnace floor, beneath the paths of the work, with preferably the blast opening under the hot outgoing work 8A to assist the rising of the air due to the heat. The cool incoming work is represented at 8B. To avoid the creation of undesirable air currents 20 in the heating chamber 2 these pairs of openings should preferably be placed in the forward half of the chamber 4 longitudinally spaced at intervals of about ten feet. Each pair of openings is intended to provide an air 25 current which will have an inducting effect on the general body of air in the forward part of the interchange chamber, and the number of pairs of openings is proportioned to the length of the general eddy desired.

In detail the openings 40 and 41 of each 30 pair (see Fig. 9) are connected to the blast and suction sides respectively of blowers 42 through conduits or passageways 43 and 44. The blowers and motors therefor are preferably located outside the furnace and the conduits or passageways are preferably built 35 into the floor and foundation.

The speed of the blowers may be controlled 40 in any suitable manner and one of the advantages of this arrangement is that the rate at which the cold ware is dried and the hot ware cooled can be accurately controlled by regulating the speed of the blower motors. I provide slide valves V for controlling the 45 flow through the conduits leading to or from the blowers. Heretofore the rate of cooling and drying has largely been controlled only by the speed of the conveyor upon which the ware is carried with the result that the furnace 50 capacity has been greatly limited. For instance, if it were desired to force a furnace by increasing the speed of the conveyor fully laden with ware two difficulties would ensue. On one hand, the work might be heated and 55 cooled too rapidly with the result of imperfection in the finished product and on the other hand, the ware would come from the furnace at abnormally high temperatures with the resulting waste in heat. According 60 to the precepts of this invention, I am able to

transfer the heat from the hot to the cold ware so that as the conveyor may be speeded without the heretofore consequent loss of heat. Furthermore, this transfer of heat from hot to cold ware, effects an even though 65 more rapid drying of the cold incoming ware with the result that the incoming work is thoroughly dried before entering the burning chamber proper.

I wish also to point out that the blowers 42 70 in effecting internal circulation of air in the preheating and cooling chamber set up, a condition which in itself has an effect comparable to that of the air screen at the furnace door. The rotation of air within the 75 preheating and cooling chamber acts in conjunction with the air screen and aids it in preventing the natural longitudinal flow of hot air from and cold air into the body of the furnace.

One other feature is to be noted in conjunction with my invention, namely, that of controlling the character of the furnace atmosphere by the air screen. Without the air 80 screen, there is a natural outflow of hot air and inflow of cold air through the furnace doors which results in the addition of fresh air to the furnace atmosphere and the consequent displacement of moisture and other gaseous products incident to the burning of 85 the ware. Were the air screen 100% efficient and were there no leaks in the furnace, the furnace atmosphere would acquire characteristics vastly different from fresh air. I believe such a condition to be not necessarily 90 desirable in all instances and therefore provide means for controlling the volume of air circulated in the screen whereby the efficiency of the screen may be controlled and whereby the natural flow of air or gas into or out of 95 the furnace doors may be permitted within controlled limits.

Thus slide valves VV are provided in the conduit 31 and in the conduits 17 and 22, 100 whereby the flow of air in the screen may be controlled. I appreciate that suitable electrical control for the blower motors might be substituted but whatever the means of control, it is my object to provide means for controlling the volume of air circulated in the 105 screen so that the efficiency of the screen as a means for preventing the natural circulation of air into and out of the furnace must be varied with the result that the character of the atmosphere in the furnace may be controlled.

Having described certain preferred embodiments and applications of my invention, it is to be understood that I do not limit myself to the forms shown but that a variety 110 of other forms may be used in practice, so long as they fall within the scope delimited by the following claims. For example, although the circulating medium is described and claimed as atmospheric air, the inven- 115 120 125 1

tion is equally applicable to the use of some other gaseous circulating medium, which might conceivably be different from the general atmosphere of the furnace and plant. It is my intention that the word "air" in the subjoined claims be interpreted with the breadth of meaning above indicated.

I claim:

1. Screens for entrance and exit openings of a heat-treating furnace through which work is passed in a continuous stream comprising a single moving body of air passing successively across said openings by continuous movement.
2. A heat exchange method operable in conjunction with a continuous conveyor furnace which comprises the continuous movement of a body of air in curtain form across the mouths of such furnace in sequence from discharge mouth to loading mouth, whereby the same air abstracts heat from material leaving and applies it to material entering the furnace.
3. The method of forming air screens simultaneously across the loading and discharge openings of a continuous conveyor furnace which comprises driving air upwardly through restricted discharge means disposed across the bottom of one opening, collecting the same air across the entire width of the top of the same opening, then passing the same air in similar manner across the other opening from the bottom to the top thereof.
4. The method of forming air screens simultaneously across the loading and discharge openings of a continuous conveyor furnace which comprises driving air upwardly through restricted discharge means disposed across the bottom of one opening, collecting the same air across the entire width of the top of the same opening, then passing the same air in similar manner across the other opening from the bottom to the top thereof and returning the same air to the point of beginning in a continuous closed path.
5. Means for forming heat-exchanging air screens across the incoming and outgoing mouths of a continuous heat-treating furnace comprising a single hood across the full width of the top of each mouth, a blast orifice across the bottom of each mouth, a suction connection at one side of each hood, air impelling means common to both furnace mouths adapted to draw air from both suction connections and discharge it to both blast orifices, all simultaneously and continuously.
6. Means for forming heat-exchanging air screens across the incoming and outgoing mouths of a continuous heat-treating furnace comprising a single hood across the full width of the top of each mouth, a blast orifice across the bottom of each mouth, a suction

connection at one side of each hood, a separate air passage from each hood suction connection to the blast orifice of the mouth, and air impelling means in each of said passages.

7. The method of heat interchange in a U-shaped enameling furnace provided with a continuous conveyor which comprises setting up a circulation of air therein about an axis parallel to the conveyor paths and of substantially permanent location longitudinally of the furnace.

8. In a U-shaped continuous conveyor heat treating furnace, heat retaining and interchanging means comprising means for inducing a substantially transverse rotation of air in the heat-interchange chamber comprising a plurality of streams of air moving with the same direction and speed across three sides of said chamber.

9. In a U-shaped continuous conveyor heat treating furnace, heat retaining and interchanging means comprising means for inducing a substantially transverse rotation of air in the heat-interchange chamber comprising a plurality of streams of air moving with the same direction and speed across three sides of said chamber.

10. In a U-shaped continuous conveyor heat treating furnace, heat retaining and interchanging means comprising means for causing a substantially non-spiral circulation of air around an axis longitudinal of the heat-interchange chamber, said means comprising a plurality of openings arranged in pairs, each pair near opposite sides of one face of said chamber, a blast and a suction means connected respectively with one of the opposed openings of each pair, a conduit connecting each pair of openings, and a circulating fan in each conduit, all of said fans being arranged to move air in the same directional sense.

11. In combination with a continuous-process heat treating furnace of the type having work passing doorways always open, an exterior overhead conveyor, work-supporting rods depending from said conveyor, and a slot for the passage of said rods, air screen means across said doorways each comprising an uninterrupted hood across the top of said furnace, a slot through said hood aligned with said furnace slot, covering means for the top of said hood comprising a plurality of plates moved by said rods, said plates overlapping and resting upon the top edges of the slot and overlapping one another endwise air discharging means across the bottom of the furnace below and of equal length with said hood, and means for causing a continuous thin blast of air between said discharge means and said hood across the full width thereof.

12. An air screen hood for a conveyor furnace opening comprising sides, a top, and an outlet at one end, two opposite sides being

70

- upwardly inclined along their upper edges thereby increasing in height toward said outlet, said hood being composed of two sections extending mutually laterally and separated to form a passage transversely through the hood, a conveyor above said hood having dependent elements movable through said passage, and means associated with said dependent elements to cover the top of said passage.
13. An eduction hood for the air screen of a conveyor furnace comprising two sections forming an operative unit, said sections being spaced apart to leave a slot for the passage of conveyor elements, shoe plates carried by said elements covering the top of said slot, said shoe plates mutually overlapping longitudinally and forming a part of the hood top.
14. A furnace having entrance and exit openings and through which work is continually passed and in which the work is raised to a maximum temperature in the course of its movement between the entrance and exit openings having in combination means for causing a forced flow of furnace atmosphere past the hot outgoing work and thence into contact with the cool incoming work whereby the incoming work is preheated by the heat from the outgoing work and means for directing blasts of air across said entrance and exit openings for preventing the natural efflux of warm furnace atmosphere and influx of cool outside atmosphere.
15. A furnace according to claim 14 wherein means are provided for controlling the rate of said forced flow of furnace atmosphere whereby the rate of preheating the incoming work may be varied.
16. A furnace according to claim 14 wherein means are provided for controlling the volume of the blast directed across said entrance and exit openings, whereby ascertainable amounts of natural efflux and inflow may be permitted through said openings.
17. A U type furnace of the class described having a burning chamber at the closed end and having entrance and exit openings at the opposite end and having a preheating and cooling chamber between said burning chamber and said openings, and having in combination means for continuously conveying work through said furnace and through said openings in oppositely moving and adjacent paths at least in said preheating and cooling chamber, means for causing a circulation of furnace atmosphere about the longitudinal axis of said preheating and cooling chamber for transferring heat from hot to cold work and means for causing a stream of air to flow across said openings to restrict the natural flow of air or gas into and out of said furnace through said openings.
18. The method of heat treating ware which consists in causing the incoming and outgoing ware to pass in adjacent streams and intercepting the paths of both streams of ware by a single moving body of air passing successively across said ware in a continuous path.
19. The method of heat treating ware which consists in abstracting the heat from ware after undergoing the process of heat treatment and creating a positive air circulation adapted to conduct the abstracted heat to other ware undergoing the process of heat treating.
20. In a furnace for heat treating ware, means for conducting incoming and outgoing ware in adjacent streams, means for creating an air screen in said furnace, said air screen comprising a body of air in constant circulation, said body including two separate sheet like sections moving upwardly toward the upper confines of said furnace, one intercepting the path of incoming ware and the other intercepting the path of the outgoing ware.
- In testimony whereof I hereunto affix my signature this 16th day of February, 1930.
